UNITED STATES PATENT OFFICE

WILLIAM STOTT, OF DETROIT, MICHIGAN

COPYHOLDER

Application filed February 23, 1928. Serial No. 256,313.

The present invention relates to improvements in copy sheet holders and more particularly to holders of this character adapted for attachment to the frame of a typewriter 5 for disposing a copy sheet in a position to be conveniently read by the typist.

The primary object of the present invention is to provide a copy holder embodying an arrangement whereby the holder may be 10 readily applied to either side of the typewriter in accordance with the typist's desire.

A further object of the invention is to provide an improved copy sheet holder embodying a corner clamp which is readily attachable to either side of the typewriter frame in a manner for adjustably supporting a rest at an inclined position so as to not interfere with movement of the typewriter carriage. 15

20 A further object of the invention is to provide a copy sheet holder embodying an arrangement whereby the rest is readily adjustable laterally of the typewriter and is readily detachable from its supporting bracket 25 and thus allowing for the supporting bracket to remain connected with the typewriter frame.

25 A still further object of the invention is to provide an improved copy sheet holder embodying an angle bracket or clamp adapted for attachment to the typewriter frame and provided with angularly related socket members adapted to be disposed in position at the front edge of the typewriter frame for 30 properly receiving a rest supporting bar when the bracket is disposed at either side of the typewriter.

35 A still further object of the invention is to provide an improved copy sheet holder 40 which may be constructed entirely from sheet metal stampings and thus allowing for economical manufacture of the holder and also result in the provision of a holder which will be extremely light in weight.

45 Other objects and advantages of the invention will be apparent during the course of the following detailed description, taken in connection with the accompanying drawing, forming a part of this specification and in 50 which drawing:

Figure 1 is a perspective view illustrating a fragmentary portion of a conventional type of typewriter and showing the improved copy holder as associated with the left hand side of the typewriter. 55

Figure 2 is a fragmentary perspective view showing the manner in which the holder is readily reversible for attachment to the right hand side of a typewriter.

Figure 3 is a plan view of the face side of the copy rest or support. 60

Figure 4 is a plan view of the rear side of the copy rest or support.

Figure 5 is an enlarged side elevation of the improved corner bracket or clamp shown 65 applied to a fragmentary portion of a typewriter frame and at the left hand side of the frame.

Figure 6 is a vertical section on line 6—6 of Figure 5 and showing the manner in which the horizontally disposed supporting bar or arm is adjustably connected to the corner bracket. 70

Figure 7 is a top plan view of the showing in Figure 5 and showing a fragmentary portion of the corner bracket broken away for illustrating the manner in which the bracket is clamped to the typewriter frame. 75

Figure 8 is an enlarged section on line 8—8 of Figure 4. 80

Figure 9 is a top plan view of a slightly modified form of corner bracket or clamp for use upon typewriters having a frame provided with a rounded corner. 85

Referring to the drawing in detail, and wherein similar reference characters designate corresponding parts throughout the several views, the letter A may designate a conventional form of typewriter and B the improved copy sheet holder for detachable connection with the frame of the typewriter A. 90

The typewriter A and which is of conventional construction embodies a frame 5 including a front rail 6 and side rails 7 which extend rearwardly at a right angle from the front rail 6 at opposite ends of the keyboard 8. Supported at an elevation above and behind the keyboard 8 is a movable carriage 9 which in its path of movement extends be- 95

yond the left hand end of the typewriter frame.

The holder B comprises an angle bracket or clamp 10 which is adapted for detachable connection with the typewriter frame 5 for 5 adjustably supporting a copy rest or support 11 at either side of the typewriter so that the rest or support will not in any way interfere with movement of the carriage 9.

Referring now to the reversible corner bracket or clamp 10, and which is preferably formed from a suitable gauge of sheet metal, the same is in the form of an angle bracket providing right angularly disposed side plate portions 12 and 14 each of which is provided 15 at its upper edge with an inwardly extending hook shaped portion providing a depending flange 15 extending in spaced parallel relation to the respective side plate portions 12 and 14. This angle bracket 10 is intended to be hooked over the top edges of the typewriter frame at the corner intersections of the rails 6 and 7 as clearly illustrated, and it will readily be seen that the bracket may be disposed at either end of the front rail 6 in accordance with that side of the typewriter to which it is desired to support the copy rest 11. As will be observed in Figure 6, the side plates 12 and 14 are of a height substantially equal to the height of the rails 6 and 7 while the depending flanges 15 extend for a substantial distance downwardly at the inner side of the rails so that the flanges 15 serve to retain the bracket in position when hooked over the rails.

Secured to each of the side plate portions 12 and 14 are socket members 16, and which socket members are each of identical construction so that either may serve to receive a horizontally disposed supporting bar or arm 17 which adjustably carries at its outer end the copy rest or support 11. The socket members 16 are of one piece construction and may be formed from metal strips of a suitable thickness and width to provide a suitable bearing surface for the bar 17. The strips forming the socket members are bent to provide a triangular shaped portion 18 forming a base portion 19 which may be welded or otherwise secured to the side plates and an angular portion 20 extending in angular relation to the face plane of the side plates as illustrated in Figures 5 and 6. The strip at the lower outer end of the angular portion 20 is then bent upwardly and then rearwardly in spaced relation above the portion 20 as at 21 so as to form a substantially rectangular shaped opening 22 extending in angular relation downwardly from the side plates. The free 55 end of the portion 21 is then secured to the side plates as by welding or the like in spaced relation above the upper end of the base portion 19. As will be observed, the supporting bar or arm 17 is of rectangular shape in cross section and of a cross sectional dimen-

sion to slidably extend thru either of the openings 22 of the bracket members so that the bar extends longitudinally of the front rail 6.

Provided in the portion 21 of each of the socket members 16 is a screw threaded opening or aperture 23 for threaded reception of a thumb screw 24 which is intended to be turned into binding engagement with the bar 17 for adjustably and removably connecting the bar to either of the socket members 16. Provided also in each of the side plates 12 and 14 to one side of their respective socket members, is a threaded aperture 25 of a diameter for threaded reception of one of the thumb screws 24. Thus it will be seen that the thumb screws 24 are interchangeable and may be threaded into either of the threaded apertures 23 or 25. Referring particularly to Figure 7 and wherein the angle bracket has been shown applied to the left hand end of the front rail 6 of the typewriter frame it will be seen that the bar 17 is positioned in the socket member carried by the side plate 12 and is held in position by threading one of the thumb screws 24 thru the socket portion 21. It will further be observed that the thumb screw has been removed from the socket member of the side plate 14 and has been positioned in the threaded opening 25 of the side plate 14 and turned into binding engagement with the side rail 7 so that this set screw acts as means for coupling the angle bracket to the typewriter frame. By now observing Figure 2 it will be seen that the only requirement necessary for attachment of the angle bracket to the right hand end of the rail 6 is to reverse the position of the thumb screws so that one of the thumb screws is positioned in the threaded opening of the side plate 12 and the companion thumb screw is threaded into the opening 23 of the socket member carried by the side plate 14.

In Figure 9 the angle bracket 10' has merely been shown with a rounded corner to allow for attachment of the bracket to typewriter frames wherein a rounded corner is formed at the juncture of the front rail 6 with the rearwardly extending side rails 7. In other respects, the angle bracket 10' is of identical construction as that of the angle bracket 10 and therefore the same reference numerals has been applied to the various sections of the bracket.

Referring now to the copy rest or support 11, the same is preferably formed from sheet metal and is rectangular shape in plan. The sheet metal rest 11 is of frame like construction embodying a bordering frame providing top and bottom rails 30 and 31 respectively and side rails 32. Connecting the bordering rails are horizontal and transverse cross rails 33 and 34 respectively. This construction of the supporting frame has been provided for materially reducing the weight of the frame

and yet providing a surface for properly receiving a sheet of paper or a note book. The lower edge of the bottom rail 31 is extended outwardly and upwardly at the face side of the rail for providing a channel 35 extending throughout the bottom edge of the rest. The upwardly turned flange 36 forming the channel 35 provides means for receiving the lower edge of the copy sheet when positioned upon the face side of the support. Extending throughout the height of each of the side rails 32 is a reinforcing strip 37, and which strips as will be observed overlie the face side of the rails and have their edges turned inwardly at the rear side of the rails as clearly illustrated in Figure 4. These reinforcing strips will permit of the copy rest being formed from sheet metal without likelihood of the rest bending when serving to support a note-book.

Secured to the rear side of the rest 11 adjacent each end of the bottom rail 31, is a pair of brackets 38 providing rectangular shaped guide openings for receiving the rectangular shaped supporting bar 17. Threaded thru each of the brackets 38 is a suitable thumb screw 39 which are intended when tightened, to prevent movement of the copy rest longitudinally along the supporting bar. As will be observed, the supporting bar 17 lies flat against the rear face of the bottom rail 31 and thus the flat copy rest 11 is disposed at an angle corresponding to the angle of the openings 22 provided in the socket members 16. It will also be observed that by so supporting the rest 11 by its lower edge so that the lower edge of the rest extends in substantially a like horizontal plane as does the front rail 6 of the typewriter frame, that such will allow for the rest to be of considerable size and yet have its upper edge disposed below the typewriter carriage 9. It will readily be seen how the copy rest can be adjusted toward and away from the side rails 7 of the typewriter frame upon operating the thumb screws 39 so as to allow the copy rest to be slid longitudinally along the supporting bar 17.

Secured at one end to the face side of one of the strengthening or reinforcing strips 37 and extending longitudinally thereof, is a suitable spring wire 40 which may be employed for retaining the copy sheet upon the rest 11.

From the foregoing description it will be apparent that a novel and improved type of copy sheet holder has been provided which is of extremely simple and light construction, and one embodying an angle bracket or clamp of such construction as to permit of the bracket to be readily applied to either side of the typewriter so that the copy rest may be supported in a like manner at either side of the typewriter. It will also be apparent that a novel arrangement has been

provided in connection with the angle bracket whereby the thumb screw for retaining the supporting arm 17 in position when the bracket is applied to one side of the typewriter, is adapted for use as means for retaining the bracket in position upon the typewriter frame when the bracket is applied to an opposite side of the typewriter frame.

Changes in detail may be made to the specific form of the invention herein shown and described, without departing from the spirit of the invention or the scope of the following claims.

I claim:

1. A copy holder comprising a bracket provided with angularly disposed side plates, similarly formed socket members carried by each side plate, and a supporting arm adapted to be removably connected with either of said socket members to be supported in a horizontal position thereby.

2. A copy holder attachment for typewriters comprising an angle bracket adapted for connection with the typewriter frame at either side thereof, similarly formed socket members carried by the angular sides of the bracket, and a supporting arm adapted for detachable connection with either of the socket members.

3. In a copy holder attachment for typewriters, a bracket embodying angularly disposed side plates having hook shaped upper ends for engaging over the upper edges of the angularly extending rails of the typewriter frame, similarly formed socket members carried by each side plate of the bracket and having openings extending in angular relation to the side plates, a supporting arm capable of insertion into the opening in either of the socket members, and means for retaining the arm in position within the socket members.

4. In a copy holder attachment for typewriters comprising a frame embodying a front rail and rearwardly extending side rails, an angle bracket for attachment to either end of the front rail embodying side plates having hook shaped upper ends for engaging over the upper edges of the rails at the meeting corners thereof, said plates each being provided with a screw threaded aperture, similarly formed socket members carried by each side plate and providing openings each having a screw threaded aperture extending thereinto of a like dimension as that of the apertures in the side plates, a supporting arm insertable into the opening of either of the socket members, and a thumb screw associated with each of the side plates and interchangeable from the threaded aperture in the socket members to the threaded aperture in the side plate whereby the thumb screws act in different capacities when the angle bracket is disposed at opposite ends of the front rail of the typewriter frame.

5. In a copy holder the combination of a bracket embodying a side plate, a socket member supported upon the side plate and constructed from a strip of metal bent to provide a triangular shaped portion having its base portion secured to the side plate and a portion above the triangular shaped portion providing a rectangular shaped opening extending in angular relation to said base portion, and a supporting arm of rectangular shape in cross section slidably fitting in said opening.

WILLIAM STOTT.
